UNITED STATES PATENT OFFICE

HENRY M. STIEGLITZ, OF ST. LOUIS, MISSOURI, ASSIGNOR TO FRANK ADAM ELECTRIC CO., OF ST. LOUIS, MISSOURI, A CORPORATION

CLAMP

Application filed March 21, 1925. Serial No. 17,318.

My invention relates to improvements in clamps especially designed for the securement of fronts or covers, to cabinets, or boxes containing electrical devices such as panel-
5 boards.

My object is to provide a device of simple, strong, durable and inexpensive construction comprising elements providing both angular and distance adjustment, relatively, whereby
10 fronts for panel board boxes may be selectively positioned and secured to fixed boxes or cabinets.

My improvements consist in the novel construction, arrangement and combination of parts as hereinafter fully, clearly and concisely described, definitely pointed out in my claims and illustrated by the accompanying drawing in which:—

Figs. 1, 2 and 3 are, respectively, an elevation, a plan view and a transverse section of the clamping element; Figs. 4 and 5 are, respectively, a plan-view and a transverse section of the swivel-nut; Fig. 6 is a view of the clamp as employed in connection with a front resting directly upon the box; and Fig. 7 is a view, similar to Fig. 6, showing the clamp as employed in connection with a front spaced away from the box.

Referring to the drawing, A designates a box or cabinet, for electrical panel-boards, or other electrical devices, and B designates a front or cover therefor.

The boxes may be either of the surface type, as shown in Fig. 6 or the flush type as shown in Fig. 7. In the surface type the cover, or front B, is directly attachable to the box A, and in the flush type the front is spaced from the box, as by plaster, or other wall surfacing, surrounding a wall cavity.

The clamp of my invention functions with equal facility and efficiency in the securing of fronts, or covers, to boxes of either surface or flush installation, and, to this end, comprises essentially an element C having arms 10 and 11, an element D having swivel connection with the element C, and an element E having variable distance relation with the element D.

By preference the element C is formed out of a single piece of sheet metal, cut and

shaped to form a substantially U-shaped body having a pair of cheeks, or sides, 12, a bridge, or connecting piece, 13, and the arms 10 and 11, formed as integral continuations of the cheeks 12. In the cheeks there are formed the bearings 14, which are relatively aligned and preferably of circular shape and in the bridge there is an opening, 15, preferably formed as a slot having a trend lengthwise of the device as a whole.

Also, by preference, the element D is formed out of a single piece of sheet metal cut and shaped to form a swivel-nut of substantially semi-circular cross section and of substantially rectangular oblong shape in plan view, and in which there is formed an opening 16 having a flange, rib, or burr, 17, and internally threaded.

The element E is by preference an ordinary screw, having a head 18, and a threaded shank 19, the head forming an abutment for seating about a hole formed in the front B and the threaded shank forming a connection providing distance adjustment between the head 18 and the element D.

Obviously with the tips of the arms 10 and 11 of the element C engaged beneath the front and a part of the box, and the screw, or element E connected with the element C, as by a threaded connection with the swivel nut, the front may be fixed to the box in selective positions, and by reason of the threaded shank of the screw (E) and the rotary mounting of the swivel, the element C may be tilted bodily and hence serve for varying types of boxes and fronts.

By preference the threads in the swivel nut (element D) and the screw (element E) are of a relatively tight fit, whereby the clamp (element C) will bodily rotate upon a turning of the screw so that the arms of the element C be properly positioned in the cabinet A, as against a side wall thereof as shown. When in this position, the element C is prevented from further rotation and the element E, upon continued rotation, draws the element D to effect a fitting and clamping of the front B to the box.

Having thus described my invention, what

I claim as new therein and desire to secure by Letters Patent is:—

1. In a device of the class described, a substantially **U** shaped clamping element, the bridge portion thereof having an elongated opening therethrough, a unitary element substantially semi-cylindrical in form and having swivel connection with the clamping element and an element having variable distance relationship with the swivelled element, and extending through the elongated opening.
2. In a device of the class described, an element having a pair of substantially parallel arms, extending lengthwise thereof, a bridge between the arms, having an elongated opening therethrough, a unitary element substantially semi-cylindrical in form and having rotatable connection with said arms, and disposed at a fixed distance from said bridge, and an element carried by the rotatable element and arranged for adjustable connection therewith through the elongated opening.
3. In a device of the class described, a one-piece clamping element comprising relatively parallel arms, extending lengthwise of the element, a substantially semi-cylindrical swivel-nut of one-piece construction, rotatably carried by and having corresponding bearing surfaces in the arms of the clamping element and a screw carried by the swivel-nut.
4. In a trim-securing clamp, in combination, a clamping screw, a one-piece body member, the screw and body member being threadedly associated to permit their relative adjustment, and an arm formed of spaced side portions having registering apertures therein, the arm being mounted for rocking movement upon the body member, and so constructed as to provide an elongated opening between said spaced side portions, such opening permitting the arm to rock through a substantial angle relative to the screw, the arm being adapted, upon relative movement of the screw and body member, for clamping actuation in opposed relation to the screw, the apertures in said arm forming bearings for said body member.

HENRY M. STIEGLITZ.
